UNITED STATES PATENT OFFICE.

THOMAS MOORE, OF DAVENPORT, IOWA.

DESIGN FOR AN EGG-CANDLER.

49,394.

Specification for Design.

Patented July 18, 1916.

Application filed April 7, 1916. Serial No. 89,721. Term of patent 14 years.

To all whom it may concern:

Be it known that I, THOMAS MOORE, a citizen of the United States of America, residing at Davenport, in the county of Scott and State of Iowa, have invented a new, original, and ornamental Design for Egg-Candlers, of which the following is a specification, reference being had to the accompanying drawing, forming part thereof.

The figure is a perspective view of an egg candler, showing my new design.

I claim:

The ornamental design for an egg candler, as shown.

THOMAS MOORE.
